UNITED STATES PATENT OFFICE.

GEORGE YOCH, OF FREELAND, PENNSYLVANIA.

ALARM.

1,035,510.

Specification of Letters Patent. Patented Aug. 13, 1912.

Application filed March 23, 1912. Serial No. 685,769.

To all whom it may concern:

Be it known that I, GEORGE YOCH, a citizen of the United States, residing at Free-
land, in the county of Luzerne and State of
Pennsylvania, have invented certain new
and useful Improvements in Alarms, of
which the following is a specification, refer-
ence being had to the accompanying draw-
ings.

10 This invention comprehends certain new
and useful improvements in signals and re-
lates particularly to a knob actuated alarm.

The invention has for its primary object
a simple, durable and efficient construction
15 of audible signal which may be easily at-
tached to the knob of a door whereby the
occupant or occupants of the room into
which the door leads may be instantly ap-
prised of the fact when the knob is turned
20 preparatory to opening the door.

The invention has for a further object an
improved construction of knob actuated
alarm the parts of which may be easily and
cheaply constructed and capable of being
25 readily assembled and not liable to get out
of order.

A still further object of the invention is
to provide a device of this type which in-
cludes a knob engaging element capable of
30 fitting and being secured to knobs of dif-
ferent sizes, so as to increase the range of
usefulness of the device, the parts being so
arranged that the device may be very
35 quickly attached to a knob when required
and very easily removed when not desired
for use. And the invention also aims to
generally improve this class of devices to
render them more useful and commercially
desirable.

40 With these and other objects in view as
will more fully appear as the description
proceeds, the invention consists in certain
constructions, arrangements and combina-
tions of the parts that I shall hereinafter
45 fully describe and claim.

For a full understanding of the invention
reference is to be had to the following de-
scription and accompanying drawings, in
which—

50 Figure 1 is a side edge view of my im-
proved alarm, showing its application to a
door knob, the latter being indicated in
dotted lines; Fig. 2 is a face view of the
device, a part being broken away; Fig. 3
55 is a horizontal sectional view, the section
being taken on a plane indicated by the line

3—3 of Fig. 1; Fig. 4 is a detail perspective
view of the knob engaging elements of the
device; and Fig. 5 is a fragmentary perspec-
tive view of the post which is designed for 60
engagement thereby.

Corresponding and like parts are referred
to in the following description and indicated
in all the views of the accompanying draw-
ings by like reference characters.

65 Referring to the drawings, the numeral 1
designates the base plate of my improved
knob actuated alarm, said base plate being
provided within its upper end with an open-
ing 2 in which a post 3 is journaled, said 70
post being also journaled in a casing 4
which, in the present embodiment of the in-
vention, is open at top and bottom and which
is formed by a metallic strap with angular
75 ends having tangs 5 clenched in perforations
6 formed in the base plate. Secured to the
post 3 and mounted within the casing 4 is a
master gear wheel 7 the teeth of which mesh
with a spur pinion 8 secured to a shaft 9
80 journaled in the base plate below the post 3. 80
The pinion 8 is mounted in a casing 10
which corresponds in formation, but is pref-
erably smaller than the casing 4, hereinbe-
fore mentioned.

85 The pinion 8 is formed on one face with
diametrically disposed pins 11 which are
received in a substantially triangular open-
ing 12 formed in the enlarged upper end of
a link 13 which is also mounted in the casing
10, between the wall thereof and the outer-
most face of the pinion. At this point it
90 will be understood that when the post 3 is
turned the pinion 8 will be rotated in a di-
rection to cause one of the pins 11 to engage
with the wall of the opening 12 and thus 95
raise the link 13.

95 The link 13 is pivotally connected at its
lower end, as at 14 with a detent or pawl 15
which is pivoted on a stud 15^a projecting
from one face of the base plate 1 and which
is formed with a hooked free end designed
100 for engagement with a cog wheel 16 which
is secured to a shaft 17 driven by a spring
motor 18 secured to the opposite face of the
base plate 1, as clearly illustrated in the
drawings. The spring 19 of said motor may
105 be easily wound by a key or handle 20, as
shown. In addition to the cog wheel 16,
the shaft 17 carries a freely pivoted and
preferably joined striker 21 which is de-
signed to engage a gong 22 held on a post
110 which is secured to the base plate 1. The

detent 15 is normally held in engagement with the cog wheel 16 by a contractile spring 23.

From as much of the description as has preceded, in connection with the accompanying drawings, it will be understood that when the post 3 is turned as before mentioned and the pinion 8 also turned thereby, one of the pins 11 will cause the link to be raised upwardly so as to release the detent 15 from the cog wheel 16, thereby permitting the motor to act to sound the alarm by the repeated engagement of the striker 21 with the gong 22. As soon as the post is released or turned back to its initial inoperative position where the two pins 11 will lie against the upper wall of the opening 12, it is clear that the spring 23 will be permitted to act to cause the engagement of the pawl 15 with the cog wheel 16 and consequently the device will be held in an inoperative condition.

As stated in the outset of the specification, it is one of the objects of my invention to provide a device of this character which may be conveniently used as an attachment for use in connection with any ordinary knob for a door. To accomplish this result, the post 3, in the present embodiment of the invention is formed at opposite sides with notches 24 designed for engagement with flanges 25 that are formed on a clip 26 which is designed for engagement with a door knob, being provided for this purpose with laterally extending curved ears 27 designed to engage over the knob. Thus it will be understood that when the clip 26 is engaged with the post, any turning of the clip will cause the post to turn also. The clip 26 is provided at one end with a flexible strap 28 carrying a hook 29, whereby a rubber band 30 or other contractile band may be engaged around said hook and also around the hooks 31 that are formed on the pins 27 so as to detachably and yet securely hold the clip upon the knob.

It will thus be seen that the device may be easily secured to a door knob on the inside of a room, so that when the latch is opened from the outside and the knob is turned, the post 3 will be also turned and the alarm sounded, in the manner hereinbefore set forth.

While the accompanying drawings illustrate what I believe to be the preferred embodiment of my invention, it is to be understood that the invention is not limited thereto but that various changes may be made in the construction, arrangement and proportions of the parts without departing from the scope of the invention as defined in the appended claims.

Having thus described the invention what is claimed is:

1. An alarm of the character described, including a base plate, a post journaled therein and adapted to be turned, a master gear wheel carried by said post, a pinion meshing with said gear wheel and formed on one face with pins, a link formed with an opening accommodating said pins, the pins being adapted to engage the wall of said opening to move the link, a pawl pivotally supported upon the base plate and connected to said link, an audible signal including a gong and a striker therefor, a spring motor arranged to operate the striker, and a cog wheel movable with the striker and designed for engagement by said pawl.

2. An alarm of the character described, including a base plate, a post journaled therein, a master gear wheel carried by said post, a casing secured to one face of the base plate and in which the post is journaled and the gear wheel mounted, another casing secured to the base plate below the first named casing, a pinion mounted in said second named casing and formed on one face with diametrically opposed pins, a link mounted in said second named casing and formed at one end with an opening receiving said pins, a pawl pivotally connected to the base plate and operatively connected to the lower end of said link, a gong carried by the base plate, a spring motor, a striker adapted for engagement with the gong and actuated by said motor, and a cog wheel movable with said striker and designed for engagement by said pawl.

In testimony whereof I hereunto affix my signature in the presence of two witnesses.

GEORGE YOCH.
